SEALING DEVICE

Francis Le Barron Lord, Bloomfield, N. J., assignor to Titelox Manufacturing Company, Montclair, N. J., a corporation of New Jersey

Application October 28, 1944, Serial No. 560,856

2 Claims. (Cl. 286—37)

1

This invention relates to improvements in sealing devices for valves and the like. In such devices, a member such as a valve stem, pump, shaft, rod or the like, reciprocates or rotates. The invention is designed to preclude leakage of the liquid, gas or other medium to be controlled, without interfering with the rotation, reciprocation, or other movement of the operative parts of the device.

It has been common, in the use of high pressure valves, for example, to provide a gasket or packing frictionally held against the valve stem. Such expedients have been found ineffective as it has been common heretofore to use a material soft enough to permit the rotating or reciprocating movement of the parts, so that the maintenance of a seal was extremely difficult. It has been found in practice that various expedients heretofore employed to attain the ends described are adversely affected by usage, with resultant leakage.

The structure of my invention is designed to overcome the objections noted above, in a positive and effective manner, which permits of the sealing of the opening through which the valve stem or the like passes, while permitting the rotation, reciprocation or other movement of the parts in operation.

The structure of my invention is adapted to be accurately adjusted in a simple manner and its features are such that leakage is effectively obviated.

It has been found, under tests, that a valve made in accordance with the invention, may be subjected to pressures far in excess of those normally used and in excess of those employed in the testing of parts, without leakage; the device does not exhibit the fatigue characteristics encountered in the use of conventional structures under prolonged testing and operating conditions.

In the drawings,

Fig. 1 is a vertical sectional view of the upper portion of a valve member embodying my invention, taken on line 1—1 of Fig. 2, in the direction of the arrows,

Fig. 2 is a horizontal, transverse sectional view thereof, taken on line 2—2 of Fig. 1, in the direction of the arrows, and

Fig. 3 is an enlarged, fragmentary, perspective view of a disc member employed in carrying out my invention.

Referring more particularly to the drawings, in Fig. 1 there is shown the upper portion of a valve embodying my invention, said upper portion comprising a bonnet 10, in which a valve

2

stem 11 is rotatably positioned, said valve stem being provided with a handle or handwheel 13 or the like at the upper end thereof. A cap member 14 is positioned on the bonnet 10, the inner walls of the cap member being tapered as at 15; the cap member is provided with a medial aperture 16 through which the valve stem passes. The cap member 14 is provided with an internal key 17, preferably integral therewith, which projects beyond the plane of the inner walls as shown in Fig. 1, said key being adapted to be received in a keyway 18 in an inner member 19, the latter being externally tapered complementarily to the walls 15 of the cap member and being internally threaded as at 20 for threaded engagement with the threaded extension 21 of the bonnet 10. The inner member 19 is vertically split as at 22 to enable the same to be contracted for initial insertion into the cap and again contracted in use, 20 as hereinafter more particularly described.

A plurality of disc members 23 are positioned in the internally tapered, recessed portion 29 of extension 21 of bonnet member 10. Said discs 23 are of similar characteristics and construction 25 except that they are, as shown in Fig. 1, of progressively varying dimensions to conform to the tapered recess 29. The discs are positioned in the recess 29 with the discs 23 of progressively smaller diameter positioned lowermost as will become apparent from an inspection of the drawings.

A description of one disc member will suffice for all; for that purpose reference is made to Fig. 3, wherein the disc 23 is shown provided with a medial aperture 24 of such diameter as to receive the valve stem 11. The upper face of the disc is provided with a circumferential recess 25 communicating with aperture 24 and the lower face of the disc is provided with a circumferential portion 26 adjacent the aperture 24, one wall of said portion 26 being parallel with the recessed portion 25 of the disc to define therewith a circumferential fin 27 adjacent the aperture 24 and projecting angularly from the disc proper. The fin 27 constitutes in effect a diaphragm which is angularly directed against the valve stem 11 and is contractable thereabout on the rotation of the cap member 14 in one direction; on rotation of said cap member in the other direction, the tension of the fin on the valve stem may be correspondingly reduced. The outer wall 28 of the disc is tapered complementarily to the internal recess 29 of the extension 21 of bonnet 10. The disc 23 is preferably molded or otherwise formed of a compound containing "oilite," graph-

ite, or of pressed-powder or molded metal, plastic or other material which is preferably saturated or coated with a lubricating material, whereby, on contraction of the disc 23, the circumferential fin 27 thereof will be contracted about the valve stem 11 to effectively seal the latter in the disc and, at the same time, permit rotation and reciprocation of the valve stem in said disc.

In operation, the parts are assembled as shown in Fig. 1; to seal the valve stem 11, the cap member 14 is rotated, advancing the inner member 19 toward the open end of the cap member of smaller diameter, contracting said inner member upon the bonnet extension 21, contracting the latter about the discs 23, which are advanced toward the narrow end of recess 29 and compressing the fins 27 on the valve stem 11. It will be apparent that, by the arrangement described, a very fine and positive adjustment of the tension of the fins on the valve stem may be obtained.

By utilizing a plurality of discs 23 of progressively varying diameters the danger of leakage is further reduced since the discs 23, in the arrangement shown and described, constitute in effect a laminated multi-fin structure wherein each fin serves as an individual sealing unit; as will be appreciated, possibility of leakage through the several fins is quite remote.

The discs 23 may be united to form a single unit or may be initially formed as a single unit; the drawings illustrate the form of invention in which the discs are formed separately to attain greater independent freedom of movement of the individual discs.

The keyway 18 is located at a predetermined circumferential point relative to the slit 22 of the internal member 19 so that one may obtain a predetermined wrapping effect to resist disengagement of the parts. If the keyway is located diametrically opposite the slit 22 (which would be at a peripheral point substantially 180° from the slit 22) then the keying of member 19 in the cap 14 would be substantially at a neutral point so that no wrapping effect would be attained. By selecting a circumferential point at which the keyway 18 is located relative to the slit 22 other than 180°, one may predetermine the wrapping effect to be attained and the tendency of the parts to resist disengagement and to favor a tightening; or loosening tendency, after assembly.

Having thus described my invention what I claim as new and desire to secure by Letters Patent, is:

1. A sealing device for a member in which a rod is positioned, comprising a cap member positioned over the first named member, said cap member being provided with tapered inner walls and with an aperture for reception of said rod, and with a key projecting beyond the plane of said inner walls, and an inner member adapted to be positioned in said cap member, said inner member being externally tapered to conform to the tapered walls of the cap member and having a keyway to receive said key, and being further provided with a vertical slit and being internally threaded for threadedly engaging the first named member, the first named member being provided with an internally recessed portion, and a disc member adapted to be positioned in said last named portion, said disc member being provided with an aperture for reception of said rod.
2. A sealing device for a member in which a rod is positioned, comprising a cap member positioned over the first named member, said cap member being provided with tapered inner walls and with an aperture for reception of said rod, and with a key projecting beyond the plane of said inner walls, and an inner member adapted to be positioned in said cap member, said inner member being externally tapered to conform to the tapered walls of the cap member and having a keyway to receive said key, and being further provided with a vertical slit and being internally threaded for threadedly engaging the first named member, the first named member being provided with an internally tapered, recessed portion, and a disc member adapted to be positioned in said last named portion, said disc member being provided with an aperture for reception of said rod and with a tapered outer wall complementary to the tapered portion of the first named member.
